UNITED STATES PATENT OFFICE.

CHARLES R. ASMUS, OF COLUMBUS, OHIO.

LAUNDRY APPLIANCE.

Application filed December 9, 1924. Serial No. 754,832.

This invention relates to improvements in laundry appliances, and has for its primary object the provision of an improved clothes washing machine, adapted primarily for use in home laundries, and wherein the washer is of improved construction operating under the principle of hot water circulation, by means of which the clothing placed within the washer is completely and effectively cleaned without necessarily employing a continuously operating means for effecting the agitation of the clothing in the washer.

In accordance with the invention there is provided a washer consisting of a boiler including spaced inner and outer sections beneath which is disposed a source of heat supply, the said sections being in inter-communication by means of perforate channels whereby when in operation the heat arising from said source of supply, is directed upon the water contained within said sections so that by a thermosiphon system of operation, the water within the sections is maintained adjacent a boiling temperature and is kept in a state of constant circulation passing continuously through the clothing contained in the inner section of the washer securing thereby a thorough cleansing or washing of the clothing or fabrics with but a minimum of wear and tear thereon.

Other objects of the invention reside in the provision of a washer of the character aforesaid which is simple and convenient to operate, of economical construction and easy to maintain in a cleanly and sanitary condition following active use thereof.

With these and other objects in view, as will appear as the description proceeds, the invention consists in the novel features of construction, combinations of elements and arrangements of parts hereinafter to be fully described and pointed out in the appended claims.

In the accompanying drawing:

Figure 1 is a vertical sectional view taken through the washer comprising the present invention,

Figure 2 is a horizontal sectional view on the line 2-2 of Figure 1,

Figure 3 is an enlarged vertical sectional view taken through the upper portion of the washer,

Figure 4 is a vertical sectional view disclosing the drain outlet for the washer, and

Figures 5 and 6 are detail views of the lower construction of the supports for the washer.

Referring more particularly to the drawings the numeral 1 designates my improved washer in its entirety. This washer comprises broadly a supporting base B and a fabric container C, which is supported upon the base B in the manner to be hereinafter set forth.

The container C comprises inner and outer liquid holding sections 2 and 3 respectively. The outer section is preferably formed from non-corrodible sheet metal, and includes a closed bottom 4, an annular outer wall 5 and an open top 6. Mounted within the section 3 and suitably secured in a stationary manner to the inner wall thereof, is a fixed supporting ring 7, and the outer wall of the inner section 2 is provided with a complementary supporting ring 8. The rings 7 and 8 are provided with angularly disposed mating surfaces, whereby when the inner section is placed within the outer section, the said inner section will be supported in connection with the ring 7 in spaced relation from the inner walls of the outer section 3. This feature of construction is clearly disclosed in Figures 1 and 3.

The inner section 2 of the washer is provided with an inverted conoidal base or bottom 9, the axial portion thereof being provided with a substantially spherical dome 10 perforated as at 11. Supported above the bottom 9 within the section 2, is a perforated false bottom 12 upon which the fabrics placed within the washer are deposited. The bottom 13 of the outer section is also formed with inclined walls to conform substantially to the configuration of the bottom 9 and to produce in the bottom of the washer a nozzle construction by means of which water circulation through the washer is promoted.

The vertical side walls of the inner and outer sections 2 and 3 are spaced as at 14, and are in communication with the space 15 existing between the bottoms 9 and 13. Adjacent to the rings 7 and 8, the wall of the inner section is perforated as at 16. In

this instance a gas burner 17 is mounted within the upper portion of the base B immediately beneath the bottom 9, so that when ignited the heat of the burner is concentrated upon the water contained within the space 15. Due to the heating of the water to a point near the boiling temperature, a thermo-siphon system of circulation is set up within the washer by means of which the water is compelled to circulate through the washer by passing from the space 15 into the vertical space 14. Further upward circulation is arrested by the rings 7 and 8, causing the water to spurt through the perforations 16 in jet formation, contacting with the contents of the inner section from all sides, the non-engaging surfaces of the ring support being angularly disposed so as to facilitate the shedding of water. The cooling water is then drawn downwardly toward the bottom of the inner section, penetrating the fabrics, and passes through the perforated false bottom 12 and through the perforated dome 10 back into the space 15, where the cycle of circulation above given is repeated. The perforations in the false bottom 12 and also in the dome 10 serve to catch soap particles or other similar matter and prevent the same from obstructing the free circulation of the water as above recited.

The top of the inner section is provided with a removable cover 18, which may carry a vertically journaled dolly 19, which extends, when the washer is in operation, into the central portion of the inner section 2, where it may engage with the clothes in the ordinary manner to provide a slight degree of agitation. However, it is not necessary that the dolly be kept in constant operation during the use of the washer, but may be used intermittently if desired to effect a very thorough cleansing action. For agitating the dolly the latter may be provided at its upper end with a pinion 20, which engages with gear teeth 21 provided upon a manually operated horizontally disposed handle 22. This handle is pivoted as at 23 upon a casting 24 carried in connection with the upper surface of the cover 18.

Also formed in the cover 18 is a relief valve 25, whereby in the event of excessive steam pressure in the top of the washer, such pressure may be automatically relieved, preventing the raising of the cover section and the loss of the fluid therein. In the operation of a washer of this type, there is a tendency for the steam pressure to lift the lid or cover 18. This permits the steam vapors to escape and when striking the colder atmosphere outside of the inner section, such vapors condense and assume a liquid form. To prevent this liquid from escaping from the washer, the wall of the outer section is extended appreciably above the line

of juncture between the cover 18 and the inner section 2, see Figure 1. By this construction in the event of the escape of the steam vapors as aforesaid the condensation thereof will occur within the confines of the washer, and such condensation will be returned to the interior of the inner section. To secure this result the inner section is provided with openings 26, by means of which the condensed vapors may be returned to the interior of the inner section. The openings 26 are out of direct communication with the vertical space 14 by the inner position of the rings 7 and 8. Handles 26' may be employed to enable the operator to lift the inner section from the outer section when the washer is not in use. By reason of the position of the relief valve 25 the vapors will be condensed on the top of the cover 18 and then returned to the inner section without spilling.

The base B consists of an annular band 27 to which is secured a plurality of fixed depending legs 28, the lower ends of these legs are equipped with blocks 29 of any suitable cushioning material, which are so disposed that regardless of irregularities in the surface upon which the washer is positioned, the legs automatically accommodate themselves to such irregularities and provide a substantial non-tilting support for the washer. The upper ends of the legs are terminated to provide rests upon which the outer section 3 is deposited, and the band 27 cooperates with said rest to prevent undue lateral movement on the part of the container C as a whole. The central portion of the outer section is provided with a depending drain pipe 30, which is secured in position by means of a wing nut 31, as shown in Figure 4. The drain pipe terminates in a horizontal extension 32 carrying a control valve 33. By the opening and closing of the valve 33 the liquid level within the washer can be regulated.

In view of the description taken in connection with the accompanying drawing it will be seen that there is provided a washer of simple, economical and efficient design. The washer involves but a minimum of moveable parts, relying principally upon the circulation of the hot water or steam within the washer to secure the desired cleansing of the fabrics therein. It is of course within the range of the invention to operate the dolly by means other than of the manual form set forth. The washer is so formed as to be capable of being maintained at all times in a cleanly and sanitary condition. The inner section may be removed from the washer, and its walls conveniently scoured whenever desired. Moreover, by reason of the elevated walls of the outer section the washer when in operation will not permit of the undue escape of liquid therefrom, all

vapors arising from the inner section of any moment are condensed and returned to the interior of the washer.

The washer is of such design as to permit of the use of polish materials in its construction so as to impart an ornamental and attractive appearance to the exterior thereof.

What is claimed is:

1. In a washing machine, a boiler comprising inner and outer sections, said sections being formed with spaced bottom and side walls, means for suspending the inner section within the outer section, consisting of a fixed ring support arranged interiorly of the outer section, and a complementary ring support stationarily projecting from the side wall of the inner section and engaging the said first named ring support, the engaging surfaces of said support being disposed on an angle with respect to the horizontal so as to center automatically the position of the inner section within the outer

section, the non-engaging surfaces of said ring support being angularly disposed so as to facilitate the shedding of water.

2. In a washing machine, a boiler comprising inner and outer sections, said sections being formed to include spaced bottom and side walls, the spaces between the vertical walls of said sections and the bottom wall thereof being in uninterrupted communication around the entire circumference of the boiler, co-acting rings carried by said sections for effecting the suspension of the inner sections within said outer sections, said rings being provided with flat reversely inclined surfaces, and a removable cover member provided upon the inner section, the walls of said outer section being terminated above the plane of intersection of the cover member with the inner section.

In testimony whereof I affix my signature.

CHARLES R. ASMUS.
